CLAIM

The ornamental design for a mounting device for a cutting tool, as shown and described.

DESCRIPTION

FIG. 1 is a front perspective view of a mounting device for a cutting tool;

FIG. 2 is a front elevational view thereof;

FIG. 3 is a right side elevational view thereof;

FIG. 4 is a top plan view thereof;

FIG. 5 is a left side elevational view thereof; and,

FIG. 6 is a bottom plan view thereof.

In the above drawing, any broken line illustration is not part of the design sought to be patented. In addition, any views not shown thereof do not form a part of the invention.
